UNITED STATES PATENT OFFICE.

WILLIAM R. HART, OF SEATTLE, WASHINGTON.

RIVETING-MACHINE.

1,284,100.

Specification of Letters Patent.

Patented Nov. 5, 1918.

Application filed February 12, 1918. Serial No. 216,827.

To all whom it may concern:

Be it known that I, WILLIAM R. HART, citizen of the United States, residing at Seattle, in the county of King and State of Washington, have invented a certain new and useful Improvement in Riveting-Machines, of which the following is a specification.

My invention relates to improvements in riveting machines and the object of my invention is to provide a riveting machine of a simple and cheap construction that may be operated with comparatively little power to clinch the ends of rivets of the form commonly used in riveting plates, beams and the like.

My invention consists in the novel construction, adaptation and combination of parts as will be more clearly hereinafter described and claimed.

I accomplish this object by devices illustrated in the accompanying drawings, wherein—

Figure 1 is a view in side elevation of a riveting machine constructed in accordance with my invention as it may appear when in an operative position;

Fig. 2 is a fragmentary view in front elevation illustrating the devices for supporting the riveting machine;

Fig. 3 is an enlarged fragmentary view partly in cross-section and partly in elevation of a detail of my invention; and

Fig. 4 is an enlarged fragmentary view partly in cross-section and partly in elevation of another detail of my invention.

Referring to the drawings, throughout which like numerals indicate like parts, the numeral 5 designates a riveting tool which is shaped like a bolt except that it is provided on its forward end with an enlarged section 6 that is recessed as at 7 for the purpose of forming a head on a rivet.

The tool 5 is slidably disposed within suitably aligned holes in two upright frame pieces 10 and 11 that are rigidly connected with each other by an integral base portion 12.

The frame piece 10 is of relatively short length but the frame piece 11 is substantially longer in length and is provided on the top end with a widened portion 13 that is bent downwardly to form a hook 14 that is adapted to hook over and slide upon a support or track member 15 that may be se-

cured, as by bolts 16, to the plates 17 that are being secured together by rivets 18.

The widened portion 13 of the frame piece 11 is provided at both ends with spring pressed pawls 20 and 21 that normally engage with the teeth of integrally formed ratchets 22 and 23 respectively on the track member 15 and prevent endwise movement of the frame portion 13 on the track member. When it is desired to shift the riveting machine sidewise on the track member 15 the pawls may be lifted out of engagement with the ratchets 22 and 23.

The riveting tool 5 is provided near the front end with a fixed collar 24 and has a helical compression spring 25 provided thereon, one end of the spring 25 bearing against the frame member 10 and the other end of the spring 25 bearing against the collar 24 so that when the tool is moved to the right as seen in Fig. 1 the spring 25 will be compressed and when the tool is released the force of the spring against the collar 24 will move the tool in the opposite direction and cause it to strike a blow.

The riveting tool 5 is provided with a conically shaped head 26, the inner side of which forms a shoulder 27 with which a plunger 29 in the end of a lever arm 28 may engage to move the riveting tool 5 from the position shown in full lines to the position shown by broken lines in Fig. 1, and thereby compress the spring 25.

The plunger is movable lengthwise within a recess in the end of the lever arm 28 and is yieldingly urged outwardly by a spring 30. The outward movement of the plunger 29 is limited by a pin 31 that extends crosswise of the plunger and is movable within slots 32 in the lever arm 28.

The lever arm 28 is fulcrumed on a pivot pin 33 in a bracket 34 that is fixedly secured to the lower portion 12 of the frame.

In operation of my riveting machine the track member 15 is secured to one of the plates that are being riveted, at the desired elevation, so that the riveting tool is supported opposite the rivet that is to be riveted. The operator then grasps the lower end of the lever arm and moves it back and forth from the position shown in full lines to the position shown in broken lines to reciprocate the riveting tool and cause it to strike and clinch the rivet.

When the lever arm is in the position

shown by full lines in Fig. 1 the plunger 29 will be engaged behind the head 26 so that when the lever arm is moved into the position shown by broken lines the riveting tool 5 will be moved to the right into the position shown by broken lines and will then be released and permitted to strike the rivet.

As the lever arm is moved back from the broken line to the full line position the inclined front side 35 of the plunger 29 will engage with the head 26 and be crowded downwardly thereby against the pressure of the spring 30 until it passes the edge of the head 26 and snaps upwardly into the position shown by full lines in Fig. 1.

In practice it may be found desirable to provide suitable mechanism whereby the lever arm 28 may be operated by turning a crank or by the use of foot power but since 20 this forms no part of my invention it is not herein shown.

It is obvious that changes in the form of construction of the various parts of my invention may be resorted to within the scope 25 of the following claims.

I claim—

1. A riveting machine of the class described, comprising two upright frame members that are rigidly connected in spaced apart relation by an integral base portion and are provided with aligned perforations, one of said upright frame members being of greater length than the other and having a hook provided on the top end 30 thereof, a riveting tool slidably mounted within the perforations in said frame members and having a recess in one end thereof that is adapted for clenching rivets, a spring connected with said rivet tool and said

frame members and adapted to urge said riveting tool in one direction, a lever arm pivotally mounted on said frame and a spring actuated plunger in the end of said lever arm for engaging said riveting tool whereby said riveting tool may be withdrawn against the pressure of said spring and then released.

2. A riveting machine of the class described, comprising two upright frame members that are secured together in spaced apart relation by an integral base portion and are provided with aligned perforations, of a riveting tool reciprocable within said perforations, a collar on said riveting tool between said upright members, a helical compression spring on said riveting tool and interposed between said collar and one of said upright members, a head on said riveting tool said head having an abrupt shoulder on its inner side, an operating lever pivotally mounted on a fixed bracket on the base portion of said frame said operating lever having a tubular bore in the upper end thereof, a plunger slidable within said bore and provided with an inclined outer end, a spring to urge said plunger outwardly, means for limiting the outward movement of said plunger, a track member for said riveting machine, a hook on the upper end of one of said frame members and adapted to hook over said track and ratchet means for fastening said hook to said track.

In witness whereof, I hereunto subscribe my name this 2nd day of February, A. D. 75 1918.

WILLIAM R. HART.
